UNITED STATES PATENT OFFICE.

NELSON M. WATSON, OF DETROIT, MICHIGAN, ASSIGNOR TO FRED WARDELL, OF SAME PLACE.

DESIGN FOR A CASE FOR COIN-CONTROLLED MECHANISM.

SPECIFICATION forming part of Design No. 34,754, dated July 9, 1901.

Application filed June 8, 1901. Serial No. 63,807. Term of patent 3½ years.

To all whom it may concern:

Be it known that I, NELSON M. WATSON, a citizen of the United States, residing at Detroit, in the county of Wayne, State of Michigan, have invented and produced a certain new and original Design for a Case for Coin-Controlled Mechanism, reference being had to the accompanying drawings, and to the figures of reference marked thereon, which form a part of this specification.

This invention relates to a design for a case for coin-controlled mechanism; and it consists in the formation and presentment illustrated in the accompanying drawings, in which—

Figure 1 is a front elevation of the case, and Fig. 2 is a side elevation thereof.

The leading feature of my design consists in a pyramidal base upon which is mounted at an incline a quadrangular case having a projecting top piece and an open face. Resting upon the base at the rear of the case and in contact with both is a side bracket, and standing laterally from opposite sides of the case are rounded knobs.

Referring to the characters of reference, 1 designates the pyramidal base, upon which the quadrangular case 2 is mounted at an angle, said case having an ornamental top piece 3. In the open face of the case is located a circular scroll 4. The bracket at the rear of the case is designated at 5, and the knobs on the sides of the case are designated at 6 and 7. The knob 7 is attached to an angular bracket 8. The front of the case is provided with a marginal border 9, the whole presenting an harmonious and ornate figure.

Having described my invention, what I claim as new, and desire to secure by Letters Patent, is—

The design for a case for coin-controlled mechanism, substantially as herein shown and described.

In testimony whereof I sign this specification in the presence of two witnesses.

NELSON M. WATSON.
